UNITED STATES PATENT OFFICE.

ANDREW F. HOWE, OF GRANITE CITY, ILLINOIS.

JOINTER-GUARD.

1,157,109.

Specification of Letters Patent. Patented Oct. 19, 1915.

Application filed July 17, 1913. Serial No. 779,569.

To all whom it may concern:

Be it known that I, ANDREW F. HOWE, a citizen of the United States, residing at Granite City, in the county of Madison and State of Illinois, have invented a new and useful Improvement in Jointer-Guards, of which the following is a specification:

My invention relates to a jointer guard, and has for its object to prevent the hands of the operator from being caught by the revolving knives while passing the material to be dressed along the table and removing it therefrom when finished.

It consists in features of novelty as hereinafter described and claimed, reference being had to the accompanying drawing forming part of this specification, whereon,

Figure 1, is a top plan of my improved jointer guard as applied to a cylindrical revolving cutter and its table (broken away); Fig. 2, a side elevation thereof; Fig. 3, a vertical cross section to enlarged scale, through the guard and cutter and corresponding longitudinal section through the table (broken away) on line 3, 3, in Fig. 1; Fig. 4, a vertical longitudinal section to enlarged scale, through the guard on line 4, 4, in Fig. 1, omitting the cutter and table, and Fig. 5, a similar view to Fig. 4, of the guard in its extreme retracted position to one side of the table (not shown).

Like letters and numerals of reference denote like parts in all the figures.

a represents a cylindrical jointer cutter mounted and revoluble in the table *b* and having the cutting edges of the knives 1 projecting, through part of their travel, above the table *b* in the usual well-known manner.

My improved jointer guard comprises a hood or main member *c* which is arranged over the jointer cutter *a* (or thereabout) transversely and parallel to the table *b*, preferably for its entire width and beyond one side thereof, and at a suitable height therefrom.

The body of the hood *c* is preferably, of an inverted trough shape in cross section having in its front and rear edges a series of notches or recesses 2 and 2' in each respectively, which are arranged side by side in line with each other, and through the end walls or solid parts 3 3' of the hood *c* between the notches 2 2', is passed a rod or bolt 4 4' respectively to which, in each notch

2 on the front side of the hood *c*, is hinged the inner end of a dependent arm or auxiliary member *d* which is preferably convex on its underside to within a short distance of the table *b* and thence directed tangentially upward to its outer end at a suitable distance from the table *b* and suitably shaped thereat, so that, on passing the material *e* to be dressed along the table *b* as indicated by the arrow in Fig. 2, the arm *d* (or arms according to the width of the material and corresponding number of arms engaged) will be engaged by the forward end of the material *e* and thereby, as the latter is advanced, and raised into the position indicated by dotted lines in Fig. 2, or so that the material *e* will pass beneath the convex underside of the arm *d*, the whole operating as a guard to prevent the hands of the operator from coming in contact with the knives 1 of the jointer cutter *a*. Similarly, to the rod 4' on the rear side of the hood *c* is hinged in each notch 2', a preferably, vertically dependent arm or auxiliary member *d'* which is suitably shaped at its bottom end within a suitable distance of the table *b*, so that as the material *e* is advanced over and rearward from the jointer cutter *a*, its forward end will engage the arm *d'* and thereby constrain it outward on its hinge 4' into the position indicated by dotted lines in Fig. 2, the bottom end of the arm *d'* in so doing bearing on the material *e* and thereby operating co-operatively with the hood *c*, as a guard for preventing the hands of the operator from coming in contact with the knives 1 when withdrawing the finished material *e* from the table *b*.

For preventing inward movement of the arms *d* about their hinge 4 when they are engaged by the material *e*, the rear side of each arm *d* is formed at its hinge 4 with a dependent lug 5 which in the normal position of the arm *d* engages with a corresponding projection 5' on the hood *c* as seen in Fig. 3. Similarly, for preventing inward movement of the arms *d'* about their hinge 4', the rear side of each arm *d'* when in its normal position, is adapted to engage a correspondingly shaped projection 6 on the hood *c*.

For supporting the hood *c* and its appendages as above described the hood *c* is formed on its under or concave side, preferably, in the middle, with a boss 7, which is

perforated centrally and longitudinally parallel to the underside of the overlying hood *c*, and through the boss 7 is passed freely, a horizontally arranged bolt 8 having at one 5 end a head 9, which in the normal position of the hood *c* and its appendages as seen in Figs. 1 and 4, bears against the outer face of the boss 7, the bolt 8 extending therefrom through the boss 7 to the end of the 10 hood *c* beyond one side of the table *b* where the other end portion of the bolt 8 passes through, and is firmly held in a boss 10, which is formed in a lever *f*, which is fulcrumed on and movable in a vertical plane 15 about a pin or stud 11 projecting from the side of the table *b*.

Projecting centrally from the outer face of, and integral with the hub 12 of the lever *f*, is a stud 12', through which, and 20 through the hub 12 the fulcrum pin 11 passes as shown, and on the stud 12' is pivoted loosely at one end, a lever *f'*, which is normally in alinement with, and rearward of the lever *f*.

25 Projecting radially from the periphery of the stud 12' is a lug 13 (Fig. 2) which is adapted to engage in a recess 13' formed part-way around the inside of the hub 14 of the lever *f'*, the latter being provided with 30 a counterbalance weight 15 which is adjustable thereon, and the whole so arranged that when the levers *f*, *f'*, are in their normal position in alinement with each other as seen in Fig. 2, the recess 13' is brought into 35 engagement at its lower end, by the weight of the lever *f'*, with the lug 13 of the stud 12', whereby the hood *c* with its appendages is normally held in place over the jointer cutter *a*.

40 The end of the bolt 8 where it passes through and beyond the lever *f* is provided with a nut 16 which is tightened against the outer face of the boss 10, the latter being clear of the under or concave side of the 45 hood *c* at all times in the operation of the parts, as hereinafter more particularly referred to, and furthermore, in this connection, from the top or convex side of the hood *c* projects upward a lug or handle 17.

50 Depending from the lever *f* adjacent to its boss 10, is a bar 18 which is preferably, T-shaped in cross section and radial to the fulcrum 11 of the levers *f*, *f'*, the bar 18 being adapted to slide frictionally tight 55 through a correspondingly shaped guide 18' fixed to the side of the table *b*.

The lever *f* is formed at its outer end beyond the boss 10, with a handle 19, whereby, when the material to be dressed by the 60 jointer cutter *a* is too thick for the automatic operation of the arms *d*, *d'* in its passage along the table *b* as described, the lever *f* with the hood *c* and its appendages can be raised by hand about the fulcrum 11 65 sufficiently to allow of the passage of the

material and the automatic action of the guard, the lever *f* when so raised being held in the desired position by the frictional grip of the bar 18 in its guide 18'. Furthermore, when desired, the lever *f* with the hood *c* 70 and its appendages may be thrown up, and over, about the fulcrum 11 in the direction of the curved arrow in Fig. 2 entirely clear of the jointer cutter *a*, in which case, when the lever *f* is in the opposite position the 75 counterbalance lever *f'*, in lieu of remaining in alinement with the lever *f* will fall to an inclined position thereto, or below the table *b*, owing to the play allowed for the lug 13 of the stud 12' along the recess 13', as indicated by the dotted lines in Fig. 2.

In applying my improved jointer guard in a case where the edge of a board or other wide material is to be dressed by the jointer cutter *a*, the hood *c* with its appendages is 80 withdrawn by its handle 17 to one side of the table *b* and beyond the lever *f* so as to uncover the jointer cutter *a* for a part of its length, the boss 7 of the hood *c* in so doing, sliding along the bolt 8 (which is held 85 fast by the boss 10 of the lever *f*) until stopped by the inner face of the boss 10 of the lever *f*, or in the position seen in Fig. 5, when the board to be dressed on its edge is 90 passed along the table *b* over the uncovered 95 part of the cutter *a*, the operator's hands being intercepted and prevented from coming in contact with the cutter knives 1 by the adjacent end of the retracted guard.

What I claim as my invention and desire 100 to secure by Letters Patent is:—

1. In a jointer guard, the combination of a hood member extending above the table and adjustable relative thereto, a plurality of separately movable fingers pivotally supported upon said hood member and extending in advance of the cutter to form a shield and supported above the table, said fingers having upwardly and forwardly directed 105 ends adapted to ride over the work presented to the cutter in such fashion that the fingers engaged by the work are swung upwardly to permit its passage, the fingers not so engaged remaining in their normal position whereby to form guards at the sides of the work.

2. In a jointer guard, the combination of a work table for supporting the material to be operated upon, a bar arranged above said table, means whereby said bar may be instantaneously adjusted to different heights above the table, a set of independently movable guard arms carried by said bar, said guard arms having their lower free ends extending upwardly and outwardly at an angle whereby when the material to be operated upon is passed under the arms it will contact with said extensions and lift the respective guard arms in its path, and means 120 carried by said bar for engaging said guard 125

arms in their normal or lower position, whereby the forwardly and upwardly extending portions of the arms are maintained in such angular relation to the work table in 5 different vertical adjustments of the bar that the guard arms are always in proper position to be lifted by contact with the ma-

terial to be operated upon irrespective of the thickness of said material.

ANDREW F. HOWE.
